(57) **CLAIM**

The ornamental design for a protective glove, as shown and described.

DESCRIPTION

FIG. 1 is a top plan showing a protective glove.

FIG. 2 is an enlarged partial top plan view taken from element 2 shown in FIG. 1; and,

FIG. 3 is a cross-sectional view taken at Line 3-3 of FIG. 2. The features shown in uniform broken lines represent environmental subject matter that forms no part of the claimed design. The dash-dot broken line style represents the perimeter of the enlarged portion of the claimed design and does not form part of the claimed design. The “dash-dot-dot” broken line style represents the boundaries of the detail views of FIGS. 2 and 3 and do not form part of the claimed design. The “dash-dash-dot-dot” broken line style in FIG. 2 illustrates the anchors for the elevation view of FIG. 3.
